TOY VEHICLE

Charles C. Blackmore, Dayton, Ohio

Application June 26, 1931. Serial No. 547,071

10 Claims. (Cl. 280—87.5)

This invention relates to a toy vehicle and more particularly to that type of toy vehicle commonly known as a coaster wagon. Many toy vehicles of this character are manufactured for 5 sale at a very low price, the coaster wagon here illustrated have a retail price of one dollar. It is necessary therefore that the construction of the vehicle be such that it can be produced at a very low cost and it is customary to build the wagons 10 almost entirely of sheet metal. This results in a low cost both as to material and as to labor but it frequently results in structural weaknesses. One place where weakness frequently develops is in the pivoted axle bar and its connection with 15 the body. Usually this axle bar is formed from a blank of sheet metal having its ends turned down to receive the axle for the wheels and having flanges to reinforce the same, the upper or horizontal part of the bar being connected with 20 the body by a single rivet or pivot pin. Such an axle bar is structurally weak and will be distorted under heavy loads or under long continued use with a normal load, and the single pivot pin or rivet frequently becomes loose or even tears out of 25 the body or of the axle bar. Another place where weakness develops is in the handle and its connection with the pivoted axle bar. Ordinarily the handle is pivoted on a bracket which is secured in some manner to the axle bar but this bracket as 30 usually constructed lacks necessary strength and the manner of connecting the handle thereto is such that both the bracket and the handle may be twisted and distorted. Further, it is customary to ship such a vehicle in a partially disassembled 35 or knock down condition. In practically all instances the wheels are removed when the vehicle is packed for shipment. When such a knocked down vehicle is received by the dealer it is usually assembled by a porter or other person having little 40 or no mechanical skill, and if the assembly is at all complicated it often happens that the parts will not be correctly assembled.

It is one object of the invention to provide a toy vehicle which will be simple in construction 45 and can be produced at a low cost and which will be of a strong durable character and can be easily assembled.

It is a further object of the invention to provide an axle bar formed of sheet metal in such a 50 manner as to give the same relatively great strength.

A further object of the invention is to provide simple efficient means for connecting such an axle bar with the body of the vehicle in a strong 55 durable manner.

It is a further object of the invention to provide a handle bracket of such a character that it can be quickly and easily assembled on the axle bar and will be held rigidly against distortion 60 when so assembled.

It is a further object of the invention to provide an improved sheet metal handle of such a character that the pivotal connection between the support and its bracket will be very strong and that the handle itself will be protected against twisting strains. 65

A further object of the invention is to provide simple easily assembled means for mounting the wheels on the axle bars.

Other objects of the invention will appear as 70 the vehicle is described in detail.

In the accompanying drawings Fig. 1 is a longitudinal sectional view of a coaster wagon embodying my invention; Fig. 2 is a section taken on the line 2—2 of Fig. 1, showing the front axle bar in rear elevation; Fig. 3 is a section taken on the line 3—3 of Fig. 1, showing a portion of the rear axle bar in front elevation; Fig. 4 is a section taken on the line 4—4 of Fig. 2; Fig. 5 is a section taken on the line 5—5 of Fig. 2; Fig. 6 is a section taken on the line 6—6 of Fig. 2; Fig. 7 is a detail view of the blank from which the handle is formed; Fig. 8 is a detail view of the completed handle; Fig. 9 is a front elevation of the axle bar showing a portion of the handle and its connecting bracket; Fig. 10 is a bottom plan view of the handle bracket; Fig. 11 is a sectional view of a slightly modified form of front axle bracket, showing the same in rear elevation; Fig. 12 is a section taken on the line 12—12 of Fig. 11; Fig. 13 is a front elevation of another modification, showing a different method of connecting the wheels with the axle bar; and Fig. 14 is a plan view of one of the axle connecting devices of Fig. 13. 85

In these drawings I have illustrated one embodiment of my invention, together with two modifications thereof but it will be understood that this embodiment has been chosen for the purpose of illustration only and that the invention may be applied to toy vehicles of various kinds and that the several parts of the invention may take various forms. 90

The vehicle here shown is a coaster wagon and comprises a body 10, preferably of sheet metal, 105 which is supported at its rear end by wheels 11 mounted on an axle bar or bolster 12, which is secured to the body of the wagon. As here shown, this axle bar is formed from a single piece of sheet metal and comprises a vertical web 13 having an upper flange 14, a lower flange 15 and end flanges 16. The upper edges of the end portions of the bar are inclined downwardly and outwardly and the upper flange is formed on these inclined edges and on the upper horizontal portion of the web. In the present instance, the flange 14 does not extend entirely across the top of the axle bar but is of sufficient size to receive attaching bolts 17 by means of which the bar is secured to the bottom of the vehicle 110

120

body. The end flanges 16 are arranged between and rigidly secured to, and preferably formed integral with, the upper and lower flanges 14 and 15, thus providing a very strong rigid axle bar which will support a relatively great weight without distortion. If desired, the central portion of the web 13 will be cut away and provided with flanges 18. The front end of the wagon body is supported by wheels 19 which are carried by a pivoted wheel supporting member or axle bar 20, sometimes called a pivoted bolster, which is pivotally connected with the body of the vehicle to permit the same to have turning movement about a vertical axis to steer the vehicle. In the present instance, this pivotal axle bar is connected with the body through a supporting member 21, and, as shown, this supporting member is formed of a single piece of metal and comprises a vertical web having its lateral edges converging downwardly and provided with rearward extending flanges 22, the upper ends of which project beyond the web and are bent into horizontal positions to receive attaching bolts 23 by means of which the supporting member is rigidly secured to the bottom of the body 10 of the vehicle. The web also has its lower portion bent rearwardly to form a bottom flange 24, the lower ends of the side flanges 22 being bent inwardly, as shown at 25, to overlap and brace the bottom flange. I also prefer to form integral with the bottom flange 24 a rearwardly and upwardly extending brace bar 26, the upper end of which is secured to the bottom of the body by a bolt 27. The lower flange 24 is of relatively short length transversely to the body and constitutes a bearing member which cooperates with a corresponding part on the axle bar 20.

The pivoted axle bar is elongated in form, being preferably of a length slightly greater than the width of the body, and comprises a vertical web 28 having an intermediate portion of its upper edge substantially horizontal and having the upper edges of its end portions inclined downwardly and outwardly. The upper edge of the web is provided with an integral flange 29 extending for the full length of the axle bar and the lower edge is also provided with a flange 30 extending for the full length of the bar. In the present instance, these flanges extend rearwardly, and at each end the web has its end portions bent rearwardly to form end flanges 31. The axle bar may be given the desired shape by either a forming operation or a drawing operation and when shaped by a drawing operation the end flanges are integral with the upper and lower flanges. The truss shape imparted to the axle bar by the inclined upper edges thereof, and the channel construction thereof, provide an axle bar which is very strong and will support relatively great weights without distortion, and when the end flanges are rigidly secured to the upper and lower flanges this strength is substantially increased. The horizontal intermediate portion of the upper flange of the axle bar, shown at 32, constitutes a bearing member which is opposed to and cooperates with the bearing member 24 of the support 21. The bearing members 24 and 32 and the lower flange 30 are provided with aligned openings and a pivot pin or king bolt 33 extends through the bottom of the vehicle body and through these openings to form a pivotal connection between the axle bar and the body. This pivot pin may be retained in place in any suitable manner, as by means of a cotter pin 34.

It will be noted that the pivot pin contacts with the bottom of the body and with the support 21 at widely separated points and that it contacts with the upper and lower flanges of the axle bar at widely separated points. Consequently the pivot pin is strongly braced against tilting movement in any direction with relation to the vehicle body, and the axle bar is braced against tilting movement with relation to the pivot pin, thereby providing a very strong rigid connection which will nevertheless permit of the free turning of the axle bar about its vertical axis.

The rear axle bar 12 and front axle bar 20 are provided with suitable means for mounting thereon the axles which carry the wheels 11 and 19. In the construction shown in Figs. 1 to 6 each axle is in two parts, each part in effect constituting a separate axle or spindle, and the connections are of such a character that the wheels may be assembled on the axle bars by merely inserting the axles through the hubs of the wheels and into suitable supporting devices in which they are automatically locked, the wheels being retained on the axles by heads on the outer ends of the latter. As here shown, the end flanges of the axle bar are provided with apertures to receive the axles, which are shown at 35, and the vertical web of the axle bar is provided with an apertured lug 36, spaced inwardly some distance from the end flange and having its aperture arranged in line with the aperture in the end flange and adapted to receive the inner end of the axle. Preferably the aperture in the lug 36 is non-circular in shape, as shown at 37, and the end of the axle is correspondingly shaped so that the axle, when inserted in the lug, will be held against rotation. In the present instance, the wheels comprise disk-like body members the central portions of which are flared inwardly and outwardly, as shown at 38, each flared portion having a flat central part. The central part of the inner web of each wheel bears against the adjacent end flange of its axle bar and the axle has a head 39 which engages the central part of the web on the outer side of the wheel and not only retains the wheel on the axle but constitutes a hub cap which is shaped to harmonize with the structure of the wheel and to impart a finished appearance thereto. The axle may be retained in position on the axle bar by any suitable means but, in the present construction, I have provided means for automatically locking the axle in position when it has been inserted in the lug 36. For this purpose the vertical web of the axle bar carries the yieldable detent 40, which may be struck from the web if desired, and this detent is bent inwardly far enough so that it will be engaged and pressed outwardly by the axle when the latter is inserted in the apertured lug 36. The axle is provided in one or both sides thereof with a notch 41 so arranged that when the axle is fully inserted in the lug 36 the detent 40 will spring into the recess, the inner wall of which then constitutes a stop which cooperates with the detent to positively prevent the withdrawal of the axle.

A coaster wagon is usually provided with a pivoted handle which may be extended in front of the vehicle for pulling the same or may be moved to an upwardly and slightly rearwardly extending position where it may be grasped by the operator, when his weight is supported on the body of the vehicle, for steering purposes. This handle is here shown at 42 and is pivotally mounted upon a connecting bracket which is secured to the piv-

oted axle bar. This bracket may be secured to the axle bar in various ways but for simplicity of construction and ease of assembly I prefer to utilize the pivot pin 33 in part for securing the 5 bracket to the axle bar. As here shown, the bracket is formed of sheet metal and comprises a top member or plate 43 having depending lateral flanges 44 and a front flange 45a, the ends of which are rigidly secured to the adjacent ends of the 10 lateral flanges and are preferably formed integral therewith, by a drawing operation. The rear portion of the top plate extends rearwardly beyond the rear edges of the lateral flanges 44 and is inserted between the bearing surface 24 of the 15 support 21 and the bearing surface 32 of the axle bar, this rearwardly extending portion of the bracket having an opening to receive the pivot pin 33 and this opening being so arranged that when the pivot pin is inserted through the same the rear 20 edges of the lateral flanges 44 will be held in contact with the vertical web 23 of the axle bar. If desired, the rear end of the top plate 41 may be bent downwardly, as shown at 45, to engage the top flange of the axle bar and thus further 25 strengthen the connection between the parts. Preferably the front flange 45 is of a comparatively shallow depth and the lower edges of the lateral flanges 44 are inclined downwardly and rearwardly and have at their rear ends portions 46 30 which extend beneath the bottom flange of the axle bar and are turned upwardly to form lugs 47 which extend through apertures in that bottom flange, thus rigidly connecting the bracket with the lower portion of the axle bar and holding 35 the same firmly against any upward movement with relation to the axle bar which might tend to bend or distort the bracket. It is also preferable that the lateral edges of the bracket should converge forwardly so as to provide the 40 same with a relatively narrow front portion adapted to be received in the forked end of the handle.

In the construction here illustrated the handle is formed from a single blank of sheet metal, the 45 shape of which is shown in Fig. 7. This blank is folded upon itself to provide the handle with a tubular intermediate portion 48 extending for the greater part of the length of the handle, and the outer end portion of the blank, shown at 49, is 50 folded upon itself to provide a loop-shaped hand grip 50 which is tubular in cross section, this being accomplished by a suitable drawing operation. The inner or lower end of the blank, 51, is folded, by a suitable drawing operation, to provide the handle with a forked end, the arms 52 of 55 which are substantially U-shaped in cross section and the outer flanges of the arms lead rearwardly and merge into the tubular intermediate portion of the handle, as shown at 53, thus providing a fork of relatively great strength. The 60 arms 52 of the fork are spaced apart sufficiently to receive between them the front end portion of the handle bracket and are connected to that bracket by means of a pivot pin 54 extending through the 65 flanged arms of the handle and through the lateral flanges of the bracket. The lateral flanges of the bracket being connected and braced one against the other by the front flange 45, and the rear ends of these flanges being braced against the axle bar it will be apparent that the connection 70 is a very strong firm one and that neither the bracket nor the handle fork can be bent or distorted under any ordinary strains to which they may be subjected. The handle is also subjected to longitudinal twisting or torsional strains,

which cause a slight relative movement of the abutting edges of the tubular intermediate portion of the handle. In order to brace the handle against twisting strains I have provided the abutting edges of the blank with interlocking portions, such as lugs 55 and recesses 56, so arranged that when the handle is formed into tubular shape the lugs will fit snugly and smoothly within the recesses and will firmly hold the abutting edges against relative longitudinal movement, thereby preventing the handle from twisting.

In Figs. 11 and 12 I have shown a slightly modified form of front axle bar adapted to utilize a one-piece axle for supporting both the front wheels, 19. The axle bar is of approximately the same shape as that hereinbefore described and comprises a vertical web 57 having upper and lower flanges 58 and 59 and end flanges 60. The end flanges are extended rearwardly, for at least a portion of their length, as shown at 61, to permit the apertures therein to be so arranged that the one piece axle 62, when inserted in the apertured end flanges, will lie in the rear of the pivot pin 33, thus permitting the axle to extend for the full length of the axle bar without interference with the pivot pin.

In Figs. 13 and 14 I have shown another form of axle bar in which the wheels may be folded into a compact position for packing without entirely detaching the same from the axle bar. As 105 there shown, the axle bar 63 is of a structure similar to that hereinbefore described but instead of mounting the axle in the end flanges and lugs I have mounted on the forward smooth face of the axle bar a bracket 64 having apertured lugs 110 65 and 66 to receive the axles 67, which carry the wheels 19; the axles being in the present instance retained in the lugs by means of cotter pins 68. This bracket is permanently connected with the axle bar on a transverse axis near the 115 outer end of the bar and, as here shown, the bracket is connected with the axle bar by means of a rivet 68. The inner end of the bracket is connected to the axle bar by a removable fastening device, such as a bolt 69. By removing the 120 bolt 69 the bracket can be swung about its permanent point of connection and the wheel positioned as shown in dotted lines in Fig. 13. When the vehicle is to be completely assembled it is only necessary to swing the bracket into a horizontal 125 position and insert the bolt 69.

While I have shown and described one embodiment of my invention and certain modifications thereof I wish it to be understood that I do not desire to be limited to the details thereof as various modifications may occur to a person skilled in the art.

Having now fully described my invention, what I claim as new and desire to secure by Letters Patent is:

1. In a toy vehicle, a body, a supporting member formed in one piece and comprising a vertical web having at its upper edge means for securing the same to the bottom of said body, having its lateral edges converging downwardly and provided with flanges and having at its lower edge an apertured flange secured at its ends to the adjacent ends of said lateral flanges, and a brace extending from the outer edge of said lower flange, an elongated member arranged in supporting relation to said supporting member and having upper and lower apertured parts spaced one from the other, a pivot pin extending from the bottom of said body and through the apertures in the lower flange of said supporting member and in 150

- said parts of said elongated member, and wheels mounted on the respective ends of said elongated member.
2. In a toy vehicle, a body, a supporting member secured to said body, a wheel carrying member secured in supporting relation to said supporting member, a pivot pin extending through said members, a handle bracket having a part extending between said members and having an aperture to receive said pivot pin, said bracket also having a part to engage the front of said wheel carrying member to brace the bracket against the same and means to hold said part in engagement with said wheel carrying member.
3. In a toy vehicle, a body, a supporting member secured to said body, a wheel carrying member secured in supporting relation to said supporting member, a pivot pin extending through said members, a handle bracket having a part extending between said members and having an aperture to receive said pivot pin, said bracket also having a part extending below said wheel carrying member and having upwardly extending lugs, said wheel carrying member having recesses to receive said lugs.
4. In a toy vehicle, a body, a supporting member secured to said body, a wheel carrying member arranged in supporting relation to said supporting member, a pivot pin extending through said members, a handle bracket formed in one piece and comprising a top plate having depending lateral flanges, said top plate extending rearwardly beyond said flanges and between said members and having an opening to receive said pivot pin, said opening being so arranged that the rear edges of said lateral flanges will be held in engagement with said wheel carrying member.
5. In a toy vehicle, a body, a supporting member secured to said body, a wheel carrying member arranged in supporting relation to said supporting member, a pivot pin extending through said members, a handle bracket comprising a top plate having depending lateral flanges, said top plate extending rearwardly beyond said flanges across the upper edge of said wheel carrying member and having means for securing the same to said wheel carrying member, and said flanges having parts extending beneath said wheel carrying member and provided with upwardly extending lugs, said wheel carrying member having recesses to receive said lugs.
6. In a toy vehicle, a body, a supporting member secured to said body, a wheel carrying member arranged in supporting relation to said supporting member, a pivot pin extending through said members, a handle bracket comprising a top plate having depending lateral flanges and a front end flange rigidly connected with said lateral flanges, said plate extending rearwardly beyond said lateral flanges and between said members and having an opening to receive said pivot pin and hold the rear edges of said lateral flanges in engagement with said wheel carrying member.
7. In a toy vehicle, a body, a supporting member secured to said body, a wheel carrying member arranged in supporting relation to said supporting member, a pivot pin extending through said members, a handle bracket comprising a top plate having depending lateral flanges and a front end flange rigidly connected with said lateral flanges, said plate extending rearwardly beyond said lateral flanges and between said members and having an opening to receive said pivot pin and hold the rear edges of said lateral flanges in engagement with said wheel carrying member.
8. In a toy vehicle, a body, a supporting member comprising a vertical web having at its upper edge means for securing the same to the bottom of said body, having its lateral edges provided with flanges and having at its lower edge an apertured flange connected with said lateral flanges, an axle bar arranged in supporting relation to said supporting member and comprising a vertical web having flanges at its upper and lower edges, said upper flange having a part opposed to the lower flanges of said supporting member, a pivot pin extending through the bottom of said body and the lower flange of said supporting member and through said axle bar, and wheels supported on the respective ends of said axle bar.
9. In a toy vehicle, a body, a supporting member comprising a vertical web having at its upper edge means for securing the same to the bottom of said body, having its lateral edges provided with flanges and having at its lower edge an apertured flange connected with said lateral flanges, an axle bar arranged in supporting relation to said supporting member and comprising a vertical web having flanges at its upper and lower edges, said upper flange having a substantially horizontal central portion opposed to the lower flange of said supporting member and having its end portions inclined downwardly and outwardly, and said lower flange of said axle bar extending in a substantially straight line to the ends of said axle bar, said axle bar having at each end thereof and between the upper and lower edges thereof means for supporting an axle theren, and a pivot pin extending through said body, said supporting member and said axle bar.
10. In a toy vehicle, a body, a supporting member secured to said body and having downwardly converging lateral portions connected at their lower ends by a substantially horizontal portion, an axle bar arranged in supporting relation to said supporting member and comprising a vertical web having a substantially straight lower edge and having a continuous upper edge, the central portion of which is horizontal and the end portions of which slope downwardly and outwardly from the respective ends of said horizontal portion, said web being provided at its upper and lower edges with flanges and the flange for the horizontal portion of said upper edge being arranged in opposed relation to the lower horizontal portion of said supporting member, a pin extending through the bottom of said body and through said supporting member and said axle bar, said axle bar having at each end thereof means for supporting an axle between the upper and lower edges thereof.

CHARLES C. BLACKMORE.

145
